UNITED STATES PATENT OFFICE.

WALTER SCHÄFFER, OF BERLIN, GERMANY.

CONNECTION FOR RUNNING INCANDESCENT LAMPS AND ARC-LAMPS IN COMMON.

1,033,275.

Specification of Letters Patent. Patented July 23, 1912.

Application filed January 13, 1910. Serial No. 537,822.

To all whom it may concern:

Be it known that I, WALTER SCHÄFFER, engineer, a subject of the Emperor of Germany, residing at Geisbergstrasse 29, Berlin, Germany, have invented certain new and useful Improvements in or Relating to Connections for Running Incandescent Lamps and Arc-Lamps in Common, of which the following is a specification.

10 My invention relates to connections for running incandescent lamps and arc lamps in common in alternate current systems employing an auto transformer.

According to my invention I connect 15 groups of incandescent lamps and groups of arc lamps with the auto transformer by substituting the series resistance of the group of arc lamps by the group of incandescent lamps, both groups being connected in series 20 to the terminals of the transformer. From one point of the auto transformer, however, which subdivides the total tension in the ratio of the tensions at the terminals of the groups of incandescent lamps and arc 25 lamps, I lead a branch line to a point of the line connecting the group of incandescent lamps with the group of arc lamps. This mode of connection is based on the following considerations: In each incandescent 30 lamp circuit the current has of course to be kept as constant as possible, because when the current varies, apart from the possibility of injuring the lamps, changes in their luminous intensity are caused. But if 35 incandescent lamps are connected in series with arc lamps and are to serve as their series resistance, this requirement of avoiding fluctuation of current is opposed by the arc lamps requiring regularly occurring 40 variation of current and potential, because regulation is effected precisely by these changes. In a circuit in which arc lamps and incandescent lamps are connected in series use therefore, cannot be made of the 45 well-known means for keeping constant the strength of current.

My new connection fulfills the requisite conditions as follows: The variations of current in the arc lamps requisite for starting 50 their regulation occur in the group of incandescent lamps to such an extent that in many instances they can be used without further preparation. Namely, if the resistance of the arcs in the arc lamps varies, and accordingly 55 the current also, a partial equalization of current takes place through the

branch line connecting the above mentioned point of the auto transformer with the lamp conductor. Compensating currents flow in the one or other direction through the equalizing line according in each case as the current has increased or diminished, and the fluctuations of current which would have occurred in the group of incandescent lamps without the equalizing line are diminished by the amount of these compensating currents. As described hereinafter, I can indeed, entirely prevent the occurrence of these fluctuations of current. Consequently my connection enables the employment of 70 incandescent lamps as series resistance for alternate current arc lamps in the most favorable manner.

Two illustrative embodiments of my invention are represented diagrammatically 75 and by way of example in the accompanying drawing, wherein:

Figure 1 shows one arrangement, and Fig. 2 shows a modified arrangement.

Referring to the drawing, 1 and 2 are the terminals of an alternating current system connected with the terminals 3 and 4 of an auto transformer. The group 5 of incandescent lamps and the group of arc lamps 6 are connected in series between the terminals 3 and 4, the incandescent lamps forming the series resistance for the arc lamps. In order to enable this without the tension at the terminals of the group of incandescent lamps varying noticeably when changes 85 in current occur, I connect a branch line 9 between a point 7 of the auto transformer and a point 8 of the lamp line. This branch is without current in the normal condition 90 of the plant. But when the resistance of the arc lamps varies, a portion of the requisite compensation current flows through the branch, and the tension at the terminals of the group of incandescent lamps accordingly 95 is varied considerably less than proportionally to the variation of the arc lamp current.

The internal resistance of the transformer coils must be proportioned corresponding 105 to the variation of tension of the arc lamps necessary for their regulation, which variation of course must and indeed can be admissible for the group of incandescent lamps.

If it is wished not to subject the incandescent lamps to these fluctuations of tension, they can be negated by interpolating 110 in series a regulating resistance 10, e. g. a

resistance of the well-known type of iron resistances. Obviously, the fluctuations of current will then be kept from the incandescent lamps and the conditions are favorable in every respect.

Under certain circumstances it may happen that the resistance of the arc lamps 6, 6 becomes exceedingly small, especially if the carbons of both the arc lamps strike together simultaneously. The portion of the auto transformer located between the points 7 and 4 would then, however, become almost currentless and that might cause an inadmissible rise of tension in the incandescent lamp circuit. To remedy this drawback with certainty, as illustrated in Fig. 2 I may insert in the arc lamp circuit, between the points 8 and 4, one or more regulating resistances 11 which are proportioned for a greater working current than the normal maximum current of the arc lamps. For example, if the arc lamps are meant for 10 amperes I adjust the regulating resistance 11 to approximately 12 amperes working current. Then so long as the current is about 10 amperes or less the regulating resistance varies the resistance in the arc lamp circuit only very slightly but increases it exceedingly as soon as the current exceeds 10 amperes, say, so that 12 amperes cannot be exceeded. In this manner coils 7, 4 are prevented from becoming currentless and consequently inadmissible rise of tension at the incandescent lamp terminals is also prevented.

I claim:—

1. In an alternating current electric lighting system, the combination with an auto-transformer, of a group of incandescent lamps and a group of arc lamps connected in series between the terminals of said transformer, a branch line having one end connected between said groups and the other end to a point of said transformer which divides the total tension thereof in the ratio of the terminal tensions of said groups, and a resistance regulator placed in series with

said group of incandescent lamps and located between the terminal of the transformer to which this group is connected and the other end of said branch line.

2. In an alternating current electric lighting system, the combination with an auto-transformer, of a group of incandescent lamps and a group of arc lamps connected in series between the terminals of said transformer, a branch line having one end connected between said groups and the other end to a point of said transformer which divides the total tension thereof in the ratio of the terminal tensions of said groups, a resistance regulator placed in series with said group of incandescent lamps and located between the terminals of the transformer to which this group is connected and the other end of said branch, and a resistance regulator connected in series with said group of arc lamps, said resistance regulators being adjusted for a somewhat greater working current than the normal current of the arc lamps.

3. In an alternating current electric lighting system, the combination with an auto-transformer, of a group of incandescent lamps and a group of arc lamps connected in series between the terminals of said transformer, a branch line having one end connected between said groups and the other end to a point of said transformer which divides the total tension thereof in the ratio of the terminal tensions of said groups, and one or more resistance regulators connected in series with said group of arc lamps, said resistance regulators being adjusted for a somewhat greater working current than the normal current of the arc lamps.

In testimony whereof I have signed my name to this specification in the presence of two witnesses.

WALTER SCHÄFFER.
